(57) **CLAIM**

The ornamental design for a nozzle for a hair styling apparatus as shown and described.

DESCRIPTION

The patent or application file contains at least one drawing executed in color. Copies of this patent or patent application publication with color drawing(s) will be provided by the Office upon request and payment of the necessary fee.

1. Nozzle for a hair styling apparatus

Fig. 1.1 is a perspective view of the nozzle for a hair styling apparatus showing my new design;

Fig. 1.2 is another perspective view thereof;

Fig. 1.3 is a left side view thereof;

Fig. 1.4 is a top view thereof;

Fig. 1.5 is a front view thereof;

Fig. 1.6 is a rear view thereof;

Fig. 1.7 is a bottom view thereof; and

Fig. 1.8 is a right side view thereof.

The portions of the design shown in the color red illustrate elements that form no part of the claimed design.
